UNITED STATES PATENT OFFICE.

FRANCIS H. PATTEN, OF EDGEWOOD PARK, PENNSYLVANIA, ASSIGNOR TO WESTINGHOUSE ELECTRIC & MANUFACTURING COMPANY, A CORPORATION OF PENNSYLVANIA.

VOLTAGE-REGULATOR MECHANISM.

Application filed December 31, 1918. Serial No. 269,148.

To all whom it may concern:

Be it known that I, FRANCIS H. PATTEN, a citizen of the United States, and a resident of Edgewood Park, in the county of 5 Allegheny and State of Pennsylvania, have invented a new and useful Improvement in Voltage-Regulator Mechanisms, of which the following is a specification.

My invention relates to voltage-regulator mechanisms and particularly to mechanisms for vibrating the contact members of voltage regulators in a manner to prevent a freezing or a sticking action between them.

One object of my invention is to provide 10 an eccentrically-mounted mechanism that shall vibrate the main-contact members of a voltage regulator in a manner to prevent a sticking action of the contact members and be substantially free from the wearing action 15 which is encountered in the cam-operated type of regulators now in service.

In many types of electrical apparatus, delicately mounted contact members are vibrated to perform certain functions and 20 freezing or sticking of the contact members will generally destroy the operativeness of the apparatus associated with the contact members. Thus, in a voltage regulator for governing the operation of a generator in 25 an automobile-lighting system, an electromagnet, which is energized in accordance with the voltage generated, is provided for selectively operating a pair of contact members to control the excitation of the generator. The contact members are delicately 30 adjusted and, in case of any sticking action between them, the operativeness of the regulator is destroyed. In the past, it has been customary to constantly agitate or vibrate 35 the contact members of a regulator by means of a constantly-rotating cam member and thus prevent the sticking of the contact members. However, such a means for preventing sticking of the contact members has been found faulty in some respects, 40 by reason of the wearing action on the cam member which, in time, destroys the adjustment or the operativeness of the regulator.

In a voltage regulator constructed in accordance with my invention, a roller or ball-bearing mechanism is mounted on a constantly rotating eccentric member, and one 45 of the main contact members of the regulator is mounted upon the outer race member of the roller bearing. Moreover, the

outer race member of the roller bearing is resiliently so restrained from rotative movement that the contact members are constantly subjected to a vibratory action which prevents a sticking action between them. 60

It should be noted that, when one of the contact members of a voltage regulator is mounted on the outer race member of a roller bearing, in the manner above set forth, 65 the contact members are subjected to a much greater wiping action than is possible in a regulator having the contact members vibrated solely by means of a cam member. Thus, when the contact members are agitated by a cam member, a vibratory action of the contact members is effected substantially in only one direction, namely, in a direction perpendicular to the contact surface, and practically no wiping action between 70 the contact members is obtained. However, when the contact members are agitated by an eccentrically-mounted roller-bearing mechanism, the contact members are not only subjected to a vibratory action in a 75 direction perpendicular to the contact surface but also to an equal amount of wiping action in a direction parallel to the contact surface.

In the accompanying drawing, Fig. 1 is a 80 diagrammatic view of a voltage-regulator system embodying my invention, and Fig. 2 is an enlarged view of the means for preventing a sticking or a freezing of the main contact members of the regulator. 85

Referring to the drawing, a generator 1, comprising an armature 2 and a field winding 3, is connected in series with a storage battery 4 and is adapted to supply energy for operating the lights or the ignition 90 system of an automobile and for recharging the battery 4. The excitation of the generator 1 and, accordingly, the voltage generated thereby, is controlled by means of an electromagnet 5, which selectively short-circuits a resistor 6 that is connected in series 95 with the field winding 3.

An energizing winding 7 for the electromagnet 5 is connected in series with a resistor 8, which is composed of a so-called "advance wire", across the terminals of the armature 2 and, accordingly, is energized in accordance with the voltage generated. An armature 9 is pivotally mounted upon the frame 10 of the electromagnet and is pro- 100

vided with a main contact member 11. The armature 9 is maintained in a retracted position by means of a spring member 12, which is connected to it and which engages 5 a stationary supporting member 13.

A contact member 14, which co-operates with the contact member 11, is mounted upon the outer race member 15 of a roller bearing 16. The inner race member for the roller bearing, which is separated from the outer race member by the ball or roller members 18, is eccentrically mounted upon a constantly-rotating shaft 19. The constantly-rotating shaft 19 may be driven by any suitable 15 source of power and is preferably directly connected to the armature 2 of the generator 1. A resilient member 20, which is connected to the stationary supporting member 13, is attached to the outer race member 15 in 20 a manner to prevent the race member having a motion of rotation but to permit such movement of the outer race member that the contact member 14 may effect a vibratory action perpendicular and parallel to the 25 contact surface between the members 11 and 14.

Inasmuch as my invention is directed particularly to the mounting and the operation of the main contact members and, as the 30 regulator illustrated is well known, the operation of the regulator will be described only briefly. The resistor 6, which is in series with the field winding 3, is short-circuited by the engagement of the contact members 11 and 14. Consequently, upon an increase in 35 voltage above normal value in the lighting system of an automobile, the electromagnet 5 is energized to attract the armature 9 and open the short circuit around the resistor 40 6. Thus, the excitation of the generator 1 is reduced and, accordingly, a reduction is effected in the voltage which is supplied thereby. In case the voltage of the generator is reduced below normal value, the 45 armature 9 is released to close the contact members 11 and 14 and, consequently, short-circuit the resistor 6 to increase the excitation of the generator 1. In practical operation of the regulator, the above operations 50 take place in a rapid and intermittent manner such that the armature 9 is constantly vibrated but at different rates, according to the voltage which is generated by the machine 1.

55 Referring to Fig. 2 of the drawing, it will be noted that the contact member 14, which is mounted upon the outer race member 15 of the roller bearing 16, is moved in a direction perpendicular to the contact 60 surface between the contact members 11 and 14 for each rotation of the shaft 19, a distance equal to twice the distance between the center of the inner race member 17 and the center of rotation of the shaft 19. Moreover, the contact member 14 will be moved 65

an equal distance in a direction parallel to the surface of contact for each revolution of the shaft 19. By reason of the wiping movement of the contact member 14 relative to the contact member 11, it is readily seen 70 that a sticking or freezing action of the contact members is prevented.

Modifications in the system and in the arrangement and location of parts may be made within the spirit and scope of my invention, and such modifications are intended 75 to be covered by the appended claims.

I claim as my invention:

1. In a regulator, a pair of contact members, an electromagnet for effecting operation of said contact members, and means for vibrating said pair of contact members in a direction perpendicular to the surface of contact and for vibrating one of the members in a direction parallel to the 80 surface of contact.

2. In a regulator, a pair of contact members, and means for vibrating said pair of contact members in a direction perpendicular to the surface of contact and for vibrating 90 said members relatively to each other an equal amount in a direction parallel to the surface of contact.

3. In a regulator, a pair of contact members, an electromagnet for operating the 95 contact members, and means for jointly vibrating the two contact members in a direction perpendicular to the surface of contact of the member and for vibrating one of the contact members an equal amount in 100 a direction parallel to the surface of contact.

4. In a regulator, a pair of contact members, an electromagnet for controlling the engagement of said members, and means comprising an eccentrically mounted roller 105 bearing for operating the contact members while in engagement to prevent a sticking action between them.

5. In a regulator, a pair of contact members, an electromagnet for controlling the 110 opening of said members, and means comprising a rotating eccentric member and a ring member mounted thereon for vibrating the contact members to prevent a freezing or sticking action between them by vibrating 115 them whenever the contact members are in engagement.

6. In a regulator, a pair of contact members, an electromagnet for controlling the opening of the contact members, resilient 120 means for biasing said contact members to a closed position, and means comprising a roller bearing for effecting substantial vibration of one of said contact members in two different planes to prevent a freezing 125 or a sticking action between the contact members.

7. In a regulator, a pair of main contact members, an electromagnet for controlling the opening of said contact members, and a 130

rotatable eccentric member having a roller bearing mounted thereon for operating said contact members to effect substantial vibration of them jointly and relatively to each other.

8. In a regulator, the combination with an electromagnet having an armature controlled thereby, and a contact member mounted on the armature, of a rotating shaft having an eccentric member mounted thereon, a roller bearing mounted on the eccentric member, and a contact member mounted on the outer race member of the roller bearing and co-operating with the armature contact member.

9. In a regulator, a pair of contact members, an electromagnet for governing said contact members, and means comprising an eccentrically mounted ring member for vibrating said contact members while in engagement with each other so as to prevent a sticking action between them.

10. In a regulator, a pair of contact members normally biased to a closed position, an electromagnet for governing the engagement of said contact members, a constantly rotating eccentric member, a roller bearing mounted on said eccentric member for operating said contact members to prevent a sticking action between them by operating said contact members while in engagement with each other.

11. In a regulator, a pair of contact members, a resilient member for normally bias-

ing said members into engagement with each other, an eccentrically mounted roller bearing for supporting one of said contact members, a resilient member for preventing a rotative movement by the outer race member of the bearing, and an electromagnet for controlling the operation of the contact members.

12. In a regulator, a pair of contact members, an electromagnet for governing the operation of the contact members, a constantly rotating eccentric member, a roller bearing mounted on said eccentric member, and having one of said contact members located on the outer race member thereof, and a resilient member for preventing a rotative movement by the outer race member of the roller bearing.

13. In a regulator, an electromagnet having a pivotally mounted armature, a contact member mounted on said armature, a constantly rotating eccentric member, a roller bearing mounted on the eccentric member, a second contact member mounted on the outer race member of the roller bearing, and a resilient member connected to said armature for normally biasing the armature to connect the two contact members.

In testimony whereof, I have hereunto subscribed my name this 17th day of Dec. 1918.

FRANCIS H. PATTEN.
